[57] CLAIM

The ornamental design for a hand-held electronic game,
as shown and described.

DESCRIPTION

FIG. 1 is a front perspective view of a hand-held electronic game showing my new design;

FIG. 2 is a rear perspective view thereof;

FIG. 3 is a top plan view thereof;

FIG. 4 is a bottom plan view thereof;

FIG. 5 is a front elevation thereof;

FIG. 6 is a rear elevation thereof;

FIG. 7 is a right side elevation thereof;

FIG. 8 is a left side elevation thereof;

FIG. 9 is a rear perspective view thereof; with the cartridge insert;

FIG. 10 is a front perspective view of a second embodiment of FIG. 1;

FIG. 11 is a front perspective view of a third embodiment of FIG. 1;

FIG. 12 is a front perspective view of a fourth embodiment of FIG. 1;

FIG. 13 is a rear perspective view of FIG. 12;

FIG. 14 is a front perspective view of a fifth embodiment of FIG. 1;

FIG. 15 is a front perspective view of a sixth embodiment of FIG. 1;

FIG. 16 is a front perspective view of a seventh embodiment of FIG. 1;

FIG. 17 is a front perspective view of a eighth embodiment of FIG. 1;

FIG. 18 is a front perspective view of a ninth embodiment of FIG. 1; and

FIG. 19 is a front perspective view of a tenth embodiment of FIG. 1.

The broken line showing of a cartridge in FIG. 9 is for illustrative purposes only and forms no part of the claim. The rear perspective view of FIGS. 10, 11, 14 through 19 is similar to as shown in FIG. 2.
